Atty.

UNITED STATES PATENT OFFICE.

JULIUS J. NEUMANN, OF CHICAGO, ILLINOIS.

MOUTHPIECE FOR SAXOPHONES.

Application filed July 14, 1922. Serial No. 574,950.

To all whom it may concern:

Be it known that I, JULIUS J. NEUMANN, a citizen of the United States, and a resident of Chicago, county of Cook, and State 5 of Illinois, have invented certain new and useful Improvements in Mouthpieces for Saxophones; and I do hereby declare that the following is a full, clear, and exact description thereof, reference being had to the 10 accompanying drawings, and to the letters of reference marked thereon, which form a part of this specification.

This invention relates to improvements in reed clamps for the mouthpieces of saxophones, clarionets and like musical instruments and consists of the matters hereinafter described and more particularly pointed out in the appended claim.

The object of the invention is to provide 20 a reed clamp by means of which the reed may be securely clamped and held on its base, may be reinforced against warping and which at the same time permits the ready and quick insertion, adjustment, or 25 removal and replacement of the reed.

This and other objects and advantages of the invention will appear as I proceed with my specification.

In the drawings:—

30 Fig. 1 is a view in side elevation of the mouthpiece of a saxophone, clarinet, or the like instrument having a reed-clamp embodying my invention.

Fig. 2 is a bottom plan view of the same.

35 Fig. 3 is a longitudinal, vertical sectional view through the mouthpiece on a enlarged scale.

Figs. 4 and 5 are cross sectional views 40 through the mouthpiece as taken on the lines 4—4 and 5—5, respectively of Fig. 3.

Fig. 6 is a perspective view of a housing member embodied in my improved reed clamp as it appears when removed from the housing.

45 Fig. 7 is a perspective view of the clamp- 10 ing plate included in my improved reed clamp.

Referring now to that embodiment of the invention illustrated in the drawings:—10 50 indicates the mouthpiece of a reed instrument provided with the improved reed clamp. Said body is preferably made of cast metal, although it may be of vulcanized rubber as usual in instruments of the kind.

55 11 indicates the part of the mouthpiece known as the "lay" surface which is formed

to receive the reed 12 and which at the rear, as indicated at 13, is made flat to provide a base against which the reed is attached and supported in a familiar manner. 15 indicates the bevel tip of the mouthpiece. As shown in the drawings, the bevel part of the tip is preferably provided with a pad 17 of yielding material such as hard rubber, which is inset in the said bevel part, being 60 held in place by means of transversely extending, overhanging flanges 16 which provide a transverse recess extending across the bevel top of the mouthpiece,—the recess being open at either end for the insertion of said pad. The said pad may be held in place by shellac or other convenient means and provides a grip for the teeth which absorbs and relieves the vibration of the instrument in a familiar manner. 70

The bottom part of the mouthpiece is formed at each side of the rear end part 13 of the "lay" surface with longitudinal shoulders 18 (see Fig. 4) at each side of and extending at right angles to the said "lay" 80 surface. 19 indicates a housing (see Fig. 6). Said housing is made of sheet metal and is in the form of a channel having laterally spaced side walls 20 and a transversely curved or arched bottom wall 21. 85 The side walls 20 of the housing engage against the longitudinal shoulders 18 and the bottom wall 21 stands below the flat part 13 of the "lay" surface 11. The housing is secured in place by means of 90 screws 22 which extend through the side walls 20 of the housing and into the body of the mouthpiece at the shoulders 18. 23^a, 23^a, indicate thumb screws which are threaded through the bottom wall 21 of the housing and are adapted to engage and hold the reed against the flat part 13 of the "lay" 95 surface 11. As shown, the said bottom wall 21 of the housing is provided with apertured threaded bosses 23 to receive said 100 thumb screws.

The thumb screws do not engage the reed directly but indirectly through the medium of a clamping plate 26 which is formed to fit between the side walls of the housing 105 and to engage the rounded, butt end of the reed, said clamping plate is provided intermediate its ends with an interiorly threaded stud 27, and the bottom wall of the housing is provided with a corresponding opening 110 25 (see Fig. 3) through which said stud extends. A thumb screw 28 is engaged in

the interiorly threaded stud 27 of the clamping plate 26 and a coiled spring 30, of a diameter large enough to embrace the end of the stud 27 which projects through the opening 25 in the bottom wall of the housing, is interposed between the outer surface of the aforesaid bottom wall of the said housing and the head 29 of the said thumb screw,—an annular flange being formed on the bottom wall of the housing to enclose and protect the said coil spring. It is manifest that since the coil spring is interposed between the head 29 of the thumb screw 28, which is threaded into the stud 27 on the clamping plate 26, that the spring will tend to draw or pull the clamping plate towards the bottom wall of the housing. Thus, when the thumb screws 23^a which, as above described, through the medium of the clamping plate, hold the base of the reed in place are unscrewed to release the clamping plate, the coil spring 30 will act against the head 29 of the thumb screw 28 to dislodge the clamping plate from its engagement with the reed, thereby breaking any connection that may have been made between the clamping plate and the reed due to moisture acquired in the process of playing the instrument, or otherwise. The tension of the spring 30 may apparently be adjusted by means of the screw 28.

The clamping plate 26 is formed so that its lateral edges may slide freely within the side walls of the housing. The thumb screws are arranged so that their pressure may be brought to bear along the median line of the reed. As the clamping plate is rounded to fit the outer surface of the reed butt the screws will thus apply an even

pressure which extends equally over the base 40 against which the reed is seated. The operation and advantages of the improved reed clamp will be apparent to those familiar with the art. A reed may be removed and replaced with certainty and precision by 45 means of the thumb screws 23^a.

While in describing my invention I have referred to certain details of mechanical construction and arrangement, it is to be understood that the invention is in no way 50 limited thereto, except as may be pointed out in the appended claim.

I claim as my invention:—

A reed clamp for a musical instrument, comprising in combination with a tubular 55 mouthpiece body provided with a lay surface for a reed, a channel shaped housing member mounted on the body and enclosing the flattened rear end part of said lay surface which provides a base for the butt 60 end of the reed, said housing member including a back wall spaced from said lay surface, a clamping plate in said housing member for engaging the butt end of said reed to hold the same against said base, 65 means carried by said back wall of the housing member for applying pressure to the clamping plate at a plurality of points along its median line, and coacting means on said back wall and on said clamping 70 plate for withdrawing said clamping plate from the butt end of the reed when the pressure applying means has been released.

In testimony that I claim the foregoing as my invention, I affix my signature this 75 5th day of July, A. D. 1922.

JULIUS J. NEUMANN.
